(57) **CLAIM**

The ornamental design for a water heater air duct adapter, as shown and described.

DESCRIPTION

FIG. 1 is a front perspective view of a water heater air duct adapter showing our new design.

FIG. 2 is a front view thereof.

FIG. 3 is a rear view thereof.

FIG. 4 is a left view thereof.

FIG. 5 is a right view thereof.

FIG. 6 is a top view thereof.

FIG. 7 is a bottom view thereof.

FIG. 8 is a front perspective view thereof, showing a single portion thereof for clarity of illustration.

FIG. 9 is a back perspective thereof, showing a single portion thereof for clarity of illustration; and,

FIG. 10 is a front view thereof, showing a single portion thereof for clarity of illustration.

The broken line showing of a water heater air duct adapter is included for the purposes of illustrating portions of the article and forms no part of the claimed design. The dot-dash broken lines define the bounds of the claimed design and form no part thereof.

1 Claim, 10 Drawing Sheets
